UNITED STATES PATENT OFFICE

STEPHAN MAX FERDINAND SCHILLING, OF SONNEBERG, SAXE-MEININGEN,
GERMANY.

DOLL.

SPECIFICATION forming part of Letters Patent No. 295,425, dated March 18, 1884.

Application filed February 4, 1884. (No model.)

To all whom it may concern:

Be it known that I, STEPHAN MAX FERDINAND SCHILLING, a subject of the Duchy of Saxe-Meiningen, Germany, residing at 5 the city of Sonneberg, in the Duchy of Saxe-Meiningen, Empire of Germany, have invented certain new and useful Improvements in Dolls, of which the following is a specification.

- 10 The porcelain, wood, or papier-maché arms of dolls, the bodies of which are made of cloth, linen, and leather, have heretofore been secured by tying a piece of suitable textile fabric to the arms and sewing said fabric to the body of the doll. For obtaining a better or increased movement of the arms wires have been placed into the same. The degree of movement obtained by such fastening devices, however, was limited and unsatisfactory.
- 15 The object of this invention is to give to the arms of doll-bodies made of cloth, linen, and leather a high degree of flexibility, so that they can be moved in every direction with great facility, without decreasing their durability; and the invention consists of a 20 doll-body provided at the shoulders with a fixed transverse tube having socket-shaped ends, and of articulated arms having ball-shaped upper ends, the jointed forearms being connected by elastic cords passing through the hollow upper parts of the arms and the 25 tube of the doll-body.
- 30 In the accompanying drawings, Figure 1 represents a front view of a doll made according to my invention. Fig. 2 is also a front view, showing the upper part of the doll-body in section; and Figs. 3 and 4 are respectively a detail vertical transverse section and a plan of the connection of the articulated 35 arms with the the fixed transverse tube of the doll-body.

Similar letters of reference indicate corresponding parts.

The doll-body B is made of cloth, linen, or leather, and filled with a suitable loose material in the usual manner. In the upper part of the body B, at the shoulder portion of the same, is arranged a transverse wooden tube, A, of cylindrical shape, as shown in Fig. 45 2. The tube A is arranged with concave

seats at its ends, which receive the ball-shaped extremities of the upper arm-sections, a a. The forearms b b are also connected by ball-and-socket joints with the upper arm-sections, a a. The forearms b b are provided with recesses b' and fixed transverse pins d d, that pass across said recesses. The pins d d serve for attaching thereto stout rubber or other elastic cords, f, which are drawn through central perforations of the upper arm-sections, a, and connected in the transverse tube A of the body by means of a strong double hook, g, bent of wire. The wire hook g connects the elastic cords f f, and holds thereby the forearms b securely in the sockets of the upper 55 arm-sections, a a, and the latter in the end sockets of the tube A, as shown clearly in Figs. 2 and 3. The tube A, with the arms connected thereto, as described, is then placed into position in the body B, and the filling 60 material worked around the same, after the body is sewed together, in such a way that the tube A is entirely covered, as shown in Fig. 1. In this manner a high degree of 65 flexibility is imparted to the arms of the doll-body by means of a cheap and durable connection.

I am aware that dolls in which the limbs are connected to the body by means of ball-and-socket joints and elastic cords have been 70 used heretofore; and I do not claim this feature, broadly.

Having thus described my invention, I claim as new and desire to secure by Letters Patent—

1. The combination of a doll-body having 80 a fixed transverse tube at the shoulder portion, with articulated arms, elastic cords secured to the arms, and means for connecting the cords within said tube, substantially as set forth.

2. The combination of a doll-body having 85 a fixed transverse tube at the shoulder portion, perforated upper arm-sections; jointed forearms having fixed transverse pins, and elastic cords that are attached to said pins, 90 passed through the upper arm-sections, and connected in the transverse tube, substantially as described.

3. The combination of a doll-body, a fixed 95 transverse tube having concave end seats or 100

sockets, upper perforated arm-sections having ball-shaped terminals, jointed forearms having recesses and fixed transverse pins, and elastic cords attached to said pins, said cords being passed through the upper arm-sections, and connected by a double wire hook within the transverse tube, substantially as specified.

In testimony whereof I have signed my name to this specification in presence of two subscribing witnesses.

STEPHAN MAX FERDINAND SCHILLING.
